Primary Examiner — Cynthia Ramirez(74) *Attorney, Agent, or Firm* — Blank Rome LLP(57) **CLAIM**

The ornamental design for a brake handle, as shown and described.

DESCRIPTION

FIG. 1 is a front perspective view of a brake handle showing our new design;

FIG. 2 is a rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.
